DETACHABLE HEEL

Ben V. Dardig, New York, N.Y.

Application October 30, 1958, Serial No. 770,638

2 Claims. (Cl. 36—36)

This invention relates generally to the field of footwear, and more particularly to an improved type of detachable heel for shoes. Devices of this type are generally known in the art, and the invention resides in specific constructional details.

One of the principal disadvantages of heel constructions of this type lies in the fact that the same may become accidentally detached from the shoe should the heel portion alone be contacted by the shoes of a person standing behind the wearer, a not uncommon occurrence in crowded places. When this happens, the heel will swing about an axis co-incident with the front edge of the heel, and become quickly detached from the heel base.

It is therefore among the principal objects of the present invention to provide an improved detachable heel construction having means for preventing the accidental detachment of the heel from the shoe in the manner above described.

Another object of the invention lies in the provision of detachable heel construction which may be readily intentionally attached and detached by the wearer with a facility comparable to that in existing prior art devices.

Still another object of the invention lies in the provision of structure of the class described and possessed of the above advantages, in which the cost of fabrication may be of a reasonably low order, with consequent wide sale, distribution and use.

A feature of the invention lies in the ready adaptability of the inventive structure to both wood-based and metal-based heel constructions.

These objects and features, as well as other incidental ends and advantages will more fully appear in the course of the following disclosure, and be pointed out in the appended claims.

In the drawing, to which reference will be made in the specification, similar reference characters have been employed to designate corresponding parts throughout the several views:

Figure 1 is a view in perspective showing a detachable heel lift formed in accordance with the present invention.

Figure 2 is a fragmentary view in perspective showing the corresponding heel-base element upon which the heel element is engaged.

Figure 3 is an exploded sectional view showing the interlocking fastener elements which comprise a part of the embodiment.

Figure 4 is a longitudinal sectional vertical view showing the heel and heel-base elements in engaged and interlocked condition.

Figure 5 is a longitudinal sectional vertical view, corresponding to that seen on Figure 4, but showing an alternate form of the embodiment.

Figure 6 is a vertical sectional view corresponding to that seen on Figure 3 but showing the parts in assembled condition.

Figure 7 is a fragmentary vertical sectional view, partly

2

in elevation, showing a second alternate form of the invention.

In accordance with the invention, the device comprises broadly: a plurality of male fastener elements 11; a plurality of female fastener elements 12, a heel base 13, and a heel lift 14, all of which comprise part of a shoe, generally indicated by reference character 15.

The heel lift 14 may be of a conventional construction, including a wood base or core 17, and a rubber tread 18. A plurality of recesses 19, 20 and 21 arranged in a triangular pattern with the recess 19 disposed rearwardly with respect to the heel part of the shoe are provided in the base or core 17, the same providing for the mounting of the female fastener elements 12 by screw means 22.

The heel base element 13 may be of leather, and is secured to the sole 23 by nails 24 in well-known manner. Distributed in areas 25, 26 and 27 corresponding to the recesses 19—21, are the male fastener elements 11, being secured to the heel base element by screw means 28.

The male fastener elements 11 are generally similar (with the exception to be hereinafter explained), and accordingly, a detailed description of one of such elements will serve to describe all. Each element includes a heel-base engaging flange 30, a beaded portion or flange 31, and a central portion 32 having an opening 33 for the entrance of screw means 28.

The female fastener elements 12 are also generally similar, and accordingly, a description of one of such elements will suffice for all. Each element includes a snap ring retaining portion 35, a resilient annular snap ring 36 disposed therein, a recess- or socket-forming portion 37 and a heel-element engaging portion 38. The 35 heel-element engaging portion 38 is provided with a central opening 39 through which the screw means 22 may pass to be engaged in the base 17 of the heel lift 14.

As best seen in Figure 3 on the drawing, such illustrating the rearwardly disposed interlocking fastener elements of the fasteners preferably employed to secure the rearward portions of the heel lift and the heel base against accidental separation, the heel engaging portion 38 is provided with a downwardly extending tab 40 which, in engaged condition, as shown in Figure 4, extends into the body of the base or core 17. The engagement of the tab 40 prevents axial rotation of the female fastener element 12 with respect to the heel lift 14. Extending over the snap ring 36 at the rearward portion thereof, is a second tab 41 which extends into the socket opening of said female fastener element and beneath which the beaded or flanged portion 31 of the male fastener element 11 engages upon said latter being mated with said female element by movement thereinto. From a consideration of Figure 4 it will be apparent that, consequent to the location of said tab 41 engagement of the male fastener elements 11 with the female fastener elements 12 may be accomplished only by first engaging the rearwardmost portion of the beaded portion 31 beneath the tab 41, following which, by using a rotational motion, the forward part of the beaded portion 31 is snapped beneath the ring 36, which rotational motion also effects engagement of the other or forward male and female fastener elements. This movement involves a counter-clockwise motion as seen on Figure 4, which is the exact opposite of that which would be encountered should the rearward portion of the heel element 14 be contacted by the foot of a person standing behind the wearer. As a consequence of the aforesaid action of the parts 31, 36 and 41, detachment of the heel lift is possible only by imparting a prying-off force to the forward edge portion of the heel lift, which force tends to tip said heel lift downwardly-forwardly.

Figure 5 is a longitudinal sectional vertical view, corresponding to that seen on Figure 4, but showing an alternate form of the embodiment. The heel lift 14 is formed of a single piece of wood or core 17, and the base 13 is formed of leather. The heel lift 14 is secured to the base 13 by a single screw 22, and the base 13 is secured to the sole 23 by a plurality of nails 24. The heel lift 14 is provided with a plurality of recesses 19, 20 and 21 arranged in a triangular pattern, and the base 13 is provided with a plurality of areas 25, 26 and 27 corresponding to the recesses 19—21, and the male fastener elements 11 are secured to the base 13 by screw means 28. The male fastener elements 11 are generally similar to those shown in Figure 4, and accordingly, a detailed description of one of such elements will suffice for all. Each element includes a heel-base engaging flange 30, a beaded portion or flange 31, and a central portion 32 having an opening 33 for the entrance of screw means 28. The female fastener elements 12 are also generally similar to those shown in Figure 4, and accordingly, a description of one of such elements will suffice for all. Each element includes a snap ring retaining portion 35, a resilient annular snap ring 36 disposed therein, a recess- or socket-forming portion 37 and a heel-element engaging portion 38. The heel-element engaging portion 38 is provided with a central opening 39 through which the screw means 22 may pass to be engaged in the base 17 of the heel lift 14. The heel lift 14 is provided with a downwardly extending tab 40 which, in engaged condition, as shown in Figure 4, extends into the body of the base or core 17. The engagement of the tab 40 prevents axial rotation of the female fastener element 12 with respect to the heel lift 14. Extending over the snap ring 36 at the rearward portion thereof, is a second tab 41 which extends into the socket opening of said female fastener element and beneath which the beaded or flanged portion 31 of the male fastener element 11 engages upon said latter being mated with said female element by movement thereinto. From a consideration of Figure 4 it will be apparent that, consequent to the location of said tab 41 engagement of the male fastener elements 11 with the female fastener elements 12 may be accomplished only by first engaging the rearwardmost portion of the beaded portion 31 beneath the tab 41, following which, by using a rotational motion, the forward part of the beaded portion 31 is snapped beneath the ring 36, which rotational motion also effects engagement of the other or forward male and female fastener elements. This movement involves a counter-clockwise motion as seen on Figure 4, which is the exact opposite of that which would be encountered should the rearward portion of the heel element 14 be contacted by the foot of a person standing behind the wearer. As a consequence of the aforesaid action of the parts 31, 36 and 41, detachment of the heel lift is possible only by imparting a prying-off force to the forward edge portion of the heel lift, which force tends to tip said heel lift downwardly-forwardly.

as first effects disengagement of the forwardmost body portion or flange 31 of the rearward male element 11 from the expandible ring 36 of the companion female element, following which the heel may be swung as necessary to disengage the rearwardmost section of said beaded portion or flange from the aforesaid second or locking tab 41. Accordingly, it will be seen that, in addition to the plurality of fastener elements serving to prevent disengagement of the heel lift by rearward movement or force, the rearward pair of fastener elements of the invention prevents accidental heel detachment resulting from more or less straight downward movement of the heel element caused by a kick or like force applied to its rear-edge portion.

In the alternate form of the embodiment shown on Figure 5, the wood base or core 17 is replaced by a metal heel plate 44, and rivet means 45 replaces the screw means 22. In this construction, the tab 46 may be positioned at the line of interconnection 47 between the rubber portion 48 and the heel plate 44. In other respects, the construction is identical with the principal form of the embodiment shown on Figure 4. It is to be observed that the tab 46 may be positioned at any desired point, since its sole function is to prevent rotation of the female element 12 with respect to the heel lift 14.

In the second alternate form of the invention, the heel base generally indicated by reference character 13 is eliminated, and the attachment of heel lift 14 is directly to the integral rear-end or heel portion of the sole 23.

I wish it to be understood that I do not consider the invention limited to the precise details of structure shown and set forth in this specification, for obvious modifications will occur to those skilled in the art to which the invention relates.

I claim:

1. In a combination heel base and detachable heel lift therefor, the improvement comprising: a pair of first and second resilient, interconnected, detachable fastener elements; said first fastener element being associated with said heel base, said second fastener element being associated with said heel lift, said second fastener element being of a female type having a socket member receiving a resiliently expandible ring therein and having a tab member connected to the socket member and extending over a segment of said expandible ring which

is disposed rearwardly with respect to said heel lift, and said first element being of a male type and having a lower outwardly extending flange adapted upon mating of said elements to move past said expandible ring and thereupon to interlock with said tab member in such a way as to prevent disengagement of the fastener elements by a rearward or a straight downward movement, whereby the lift is detachably yet securely fastened to the heel base.

2. In a combination heel base and detachable heel lift therefor, the improvement comprising: pairs of first and second resilient, interconnected, separable fastener elements, said first fastener elements being associated with the heel base, said second fastener elements being associated with said heel lift, one pair of first and second fastener elements being located at the rear of said heel base and lift, the second fastener element of said pair being of a female type having a socket member receiving a resiliently expandible ring therein and further having means extending within the socket of said socket member and at a segment thereof which is disposed rearwardly with respect to said heel lift, and the first fastener element of said one pair being of a male type adapted to mate with said second fastener element and having a lower, outwardly extending flange adapted upon mating of said fastener elements to move past said expandible ring and thereupon interlock with said means in such manner as to prevent disengagement of the mated fastener elements by a rearward or straight downward movement, whereby the lift is detachably yet securely fastened to the heel base.
